UNITED STATES PATENT OFFICE.

RUDOLPH HOFFMAN, OF KANKAKEE, ILLINOIS, ASSIGNOR TO SEARS, ROEBUCK AND CO., OF CHICAGO, ILLINOIS, A CORPORATION OF NEW YORK.

OIL BURNER.

Application filed July 12, 1919. Serial No. 310,429.

To all whom it may concern:

Be it known that I, RUDOLPH HOFFMAN, a citizen of the United States, residing at Kankakee, in the county of Kankakee and 5 State of Illinois, have invented certain new and useful Improvements in Oil Burners, of which the following is a specification.

The invention relates to blue flame oil burners and has for its object the provision of 10 a burner of high efficiency, involving an improved arrangement of the combustion tubes for facilitating the lighting operation and for preventing oil from creeping from the wick onto the combustion tubes; and also 15 including the provision of an improved wick stop device carried wholly by the inner combustion tube so as to be removable therewith as a unit, and the provision of means for facilitating the removal of charred portions 20 of the wick.

In the accompanying drawings wherein I have illustrated a preferred embodiment 25 of the invention, Figure 1 is a side elevation of the improved burner. Fig. 2 is a horizontal section taken in the plane of line 2—2 of Fig. 3. Fig. 3 is a vertical sectional view through the burner taken approximately in the plane of line 3—3 of Fig. 2. Fig. 4 is a fragmentary detail view showing 30 the construction of the means for supporting the outer combustion tube. Figs. 5 and 6 are fragmentary detail views showing one form of wick scraping means. Figs. 7 and 8 are similar views showing another form 35 of wick scraping means. Figs. 9 and 10 are detail views showing a modified form of wick stop device.

Considered generally, the burner comprises the usual concentric wick tubes 1 and 40 2 spaced apart to receive a wick 3; an outer combustion tube 4 adapted to be seated upon the outer wick tube 1; and an inner combustion tube 5. 6 indicates a rod by means of which the wick stop device including a series of stop fingers 7 is manually operable 45 to move the fingers into and out of position above the wick.

The wick tubes 1 and 2 may be of any 50 suitable construction being held in spaced relation and closed at their lower ends to form an oil trough, in the usual manner. The outer tube 1 carries the usual wick raising and lowering device 8 for the wick 3, and near the upper end of said tube there 55 is provided an outwardly extending bead 9

which forms a seat for the outer combustion tube when in normal or operative position.

The outer combustion tube 4, which may be of ordinary construction, is movable independently of the inner combustion tube and at its lower end is provided with an annular member 10 adapted to cooperate with a series of stationary pins 11 to support the tube in raised position with reference to 60 the outer wick tube 1. Said annular member is fixed upon the outer periphery of the tube 4 and flares downwardly and outwardly so as to carry at its lower edge a short distance beyond the vertical plane of the outer 65 wick tube, a series of depending portions or lugs 12. These lugs are equidistantly spaced apart and are provided with central notches 13 (Fig. 4) for receiving the pins 11. Said pins are mounted upon the outer wick tube 70 in any suitable way and are also equidistantly spaced apart.

The parts are so proportioned and arranged that when the lugs are supported upon the pins the combustion tube 4 is supported in raised position with its lower end a substantial distance above the wick, and when the lugs are moved off from the pins with the latter engaging with the annular member 10 between adjacent lugs, the lower 75 edge of the combustion tube rests in lowered or operative position upon its seat 9. To permit of the easy movement of the tube 4 into either raised or lowered position, the opposite edges of the lugs are inclined as at 14 so that it is only necessary to give the tube a short turn. This may be conveniently accomplished by grasping the handle 15 (Fig. 1) forming part of the means for supporting the burner drum (not 80 shown). It will be seen that the construction and also the operation necessary to effect a change in the position of the outer tube 4, are very simple and that when the tube is raised not only is oil effectively prevented from creeping up onto the combustion tube from the wick 3, but ready access 85 to the wick is permitted from practically any side of the burner.

The inner combustion tube 5 is made of 90 a diameter somewhat less than the inner wick tube 2 and is normally fixed against vertical movement. Said tube has a closed top 16 and at its lower end has a tubular extension 5a depending into the inner wick tube. 95

To hold the combustion tube 5 properly spaced with reference to the inner wick tube, the tubular extension 5^a is provided with a series of raised portions or bosses 17. By reason of such spaced relation of the inner combustion tube relative to the inner wick tube, oil is prevented from creeping onto the combustion tube.

The means for supporting the combustion tube 5 comprises a tubular stem 18 mounted centrally of the burner upon a cross bar 19 suitably secured to the lower ends of the wick tubes 1 and 2. Near its upper end said stem is shouldered to form a seat for a washer 20 and the extreme upper end thereof, which is adapted to be passed up through a central aperture provided in the top 16 of the tube 5, is threaded to receive a wing nut 21 fixed against turning as by means of a key 21^a. The wing nut serves to clamp the top sufficiently loosely upon the stem to permit of the rotation of the combustion tube relative to the stem for a purpose to be hereinafter set forth. At its lower end, the tubular stem is internally threaded to receive a pointed screw-threaded stud 22 carried by the bar 19. It will be apparent that the inner combustion tube 5 is supported wholly by the stem 18 and may be readily removed when desired as for the purpose of removing charred portions of the wick which may have accumulated in the annular space between the inner wick tube 2 and the inner combustion tube 5.

Operable within the upper portion of the tubular stem 18 is the operating rod 6 of the wick stop device. At its lower end this rod is fixed to an inverted frusto-conical member 23 which is adapted when operated vertically by means of the rod 6 to control the positions of the stop fingers 7. A plurality of said fingers are provided, being entered through openings provided in the wall of the inner combustion tube a short distance above the upper ends of the wick tubes and spaced apart substantially equidistantly throughout the circumference of said combustion tube. Said fingers are herein formed integrally with the upper ends of a plurality of spring arms 24 connected at their lower ends by means of a ring 25 which is of a diameter somewhat less than the diameter of the inner combustion tube.

To permit of the passage of air upwardly into the upper portion of the inner combustion tube the side walls of the conical member 23 may be perforated and it is also provided with a perforated top wall 26. Upon the under side of said top wall is suitably secured a cross bar 27 into which bar is screw-threaded the lower end of the operating rod 6 which is also provided with a lock nut 28 to prevent it from unscrewing. To accommodate said bar the stem is provided in opposite sides centrally thereof with a

pair of slots 29 (Fig. 2) of a width adapted to neatly receive the bar. Said slots are made of sufficient length to permit of the operation of the conical member 23 by means of the rod 6. This rod may be provided at its upper end with a finger loop 30 for convenience in manipulating the same.

The parts are so arranged that when the member 23 is in its uppermost position the stop fingers 7 are held by their respective arms 24 in their innermost position, the inward movement thereof being limited by upturned flanges 31 on the outer ends of the fingers arranged to engage with the wall of the combustion tube 5 adjacent the openings 30 therein for the fingers; and when the member 23 is forced downwardly into the position shown in dotted lines in Fig. 3, the fingers are moved radially outwardly over the wick 3 against the action of the spring arms 24. For holding the member 23 in its raised position, its upper peripheral edge is adapted to spring into a groove formed between a pair of annular heads 32. This is the normal position of the member 23, it being desirable after the stop fingers 7 have served their purpose in positioning the wick to cause them to be withdrawn out of the flame of the lighted wick. In Figs. 9 and 10 however, I have shown a form of wick stop device in which stop fingers 7^a are immovable laterally with reference to the inner combustion tube, being formed integral with a ring 33 fixed upon the outer periphery of the inner combustion tube.

For scraping the wick to remove charred portions thereof, the stop fingers may also be employed, it being only necessary to bring them and the wick 3 into operative association and rotate the inner combustion tube, such rotation being possible by reason of the fact that the top 16 of the tube is clamped between the washer 20 and nut 21, as above set forth, with sufficient looseness to permit of its rotation relative thereto. Such rotatable mounting of the inner combustion tube also permits of a change from time to time of the positions of the stop fingers with reference to the wick, this being particularly advantageous in case of the stop fingers 7^a which, since they constantly overlie the wick, tend to cause an uneven burning thereof if their positions are never changed.

In order to more effectively remove the charred portions of the wick than can be done by the stop fingers 7 or 7^a I prefer to employ a scraper especially adapted for this purpose. In Figs. 5 and 6 I have shown a scraper 34 having two angularly disposed upright walls provided at their ends with securing flanges which may be riveted to the side wall of the inner combustion tube 5; and in Figs. 7 and 8, I have shown a scraper 35 having only one angularly disposed wall

also provided with a securing flange. One or more of these scrapers is conveniently positioned above the wick 3 so that the latter may be raised into engagement with their lower edges and the charred portions of the wick effectively removed by simply rotating the combustion tube by which the scrapers are carried.

It will be seen that I have produced a burner of a thoroughly practical character. Both combustion tubes may be supported in a manner to effectively prevent the creepage thereonto of oil from the wick; the outer tube may be readily manipulated to facilitate the lighting and extinguishing operations; the wick stop device may be quickly and easily operated to position the stop fingers in their operative or inoperative positions, as may be desired; the charred portions of the wick may be easily and effectively removed therefrom; and the parts may be readily disassembled when desired for purposes of cleaning or repair.

While I have herein illustrated and described my invention with considerable particularity, I recognize that various changes may be made in construction and arrangement without departing from the spirit and scope of the invention as expressed in the appended claims.

I claim:

1. An oil burner comprising, in combination with a pair of concentric wick tubes and an outer combustion tube, an inner combustion tube having a central supporting stem and provided with a plurality of openings adjacent the upper end of the inner wick tube, a plurality of spring arms having laterally extending fingers projecting through said openings in the inner combustion tube, and a frusto-conical member guided for vertical movements by said stem and adapted to move said fingers outwardly against the action of said spring arms.

2. An oil burner comprising, in combination with a pair of concentric wick tubes and an outer combustion tube, an inner combustion tube having a central tubular stem, a transverse member carried by the inner wick tube and adapted to support said stem, a plurality of wick stop fingers movable radially with reference to said inner combustion tube, a frusto-conical member adapted to operatively engage said fingers and having a cross bar, said stem being slotted to receive said cross bar and to permit of its vertical movement relative thereto, and an operating rod for said conical member passing through said stem and secured to said cross bar.

3. An oil burner comprising, in combination with a pair of concentric wick tubes and an outer combustion tube, an inner combustion tube having a central supporting stem rigid with reference to said wick tubes, a

plurality of wick stop fingers movable radially with reference to said inner combustion tube, and a frusto-conical member movable vertically with reference to said stem and adapted to control the positions of said fingers with reference to a wick carried by said wick tubes.

4. An oil burner having, in combination with a pair of concentric combustion tubes, a wick stop device comprising a plurality of radially movable fingers and means for moving said fingers including a frusto-conical member and an operating rod therefor extending upwardly through the inner combustion tube.

5. An oil burner having, in combination with a pair of concentric combustion tubes, a wick stop device comprising a radially extending finger and means for moving said finger while the inner combustion tube is in operative position comprising a member adapted to slidably engage with said finger, and a rod operable manually to move said member and thereby said finger.

6. An oil burner having, in combination, an inner combustion tube, a wick stop finger movable radially of said tube, and means for moving said finger comprising a vertically movable member frictionally engaging with said tube in one position of the member, whereby the member is held in such position.

7. In an oil burner, the combination with a pair of concentric wick tubes adapted to receive a wick therebetween for vertical movement, of a wick stop device for limiting the vertical movement of the wick, said device comprising a finger movable radially with respect to said tubes, means for actuating said finger into and out of position over the wick, including a member slidably engaging the finger, and means for maintaining the last mentioned means in its inoperative position.

8. In an oil burner, the combination with a pair of concentric wick tubes having a wick movable longitudinally therebetween, of means operable from a position at one side of the wick to an operative position over the wick whereby to limit the upward movement thereof, and means for actuating the last mentioned means including a member adapted to frictionally engage the same whereby to hold the first mentioned means in operative position and means for moving said member.

9. In a blue flame oil burner the combination with a vertically movable wick, of a wick stop member movable into and out of operative position with respect to said wick, a pair of combustion tubes mounted concentrically with respect to each other and said wick, and means extending upwardly through one of said combustion tubes for actuating said member.

10. In an oil burner, the combination with a vertically movable annular wick, a movable cam member located concentrically of said wick, a plurality of wick stop devices located between said cam member and said wick, and means for moving said cam member into and out of operative engagement with said wick stop devices whereby to effect their movement either from an inoperative position at the inner side of the wick or to an operative position over the wick. 45
11. A blue-flame oil burner having, in combination with a vertically movable wick, a wick stop device comprising a stop finger, a vertically movable member, and means for operating said member to move the finger outwardly, said member being adapted to frictionally hold the finger in its outer position. 50
12. A blue-flame oil burner having, in combination with a vertically movable wick, a wick stop device comprising a stop finger, a vertically movable member to actuate the finger, and a pull-rod for operating said member. 55
13. A blue-flame oil burner having, in combination with a vertically movable wick, a wick stop device comprising a stop finger and means including a slide rod operable to move the stop finger radially and adapted to hold it in its extended position so as to be engagable by the upper end of the wick. 60
14. An oil burner having, in combination, an inner combustion tube, a wick stop finger movable radially of said tube, and a manually operable member movable relative to the combustion tube and having a cam engagement with said finger to actuate it. 65
15. In an oil burner, the combination with a vertically movable annular wick, a wick stop finger movable into and out of the path of movement of said wick, a vertically movable member having a sliding engagement with said finger to actuate it, and means for operating said member including a central actuating member disposed coaxially of the wick and operatively connected with said member. 70
16. In an oil burner, the combination of an annular wick mounted for up and down movement, a combustion tube operatively associated with said wick, a wick stop finger movable radially with reference to said wick and said tube into and out of the path of movement of the wick, and means for actuating said finger including a member having a sliding cam engagement with said finger and a member extending longitudinally through said combustion tube beyond one end thereof and having an operative connection with the first member. 75
17. In an oil burner, the combination of an annular wick mounted for up and down movement, a combustion tube operatively associated with said wick, a wick stop finger movable into and out of the path of up and down movement of said wick, a cam member adapted to operatively engage said finger to actuate it, manually operable means for actuating said member, and means for holding said member in inoperative position. 80
18. In an oil burner, the combination of an annular wick mounted for up and down movement, a pair of spaced concentric combustion tubes operatively associated with said wick, the inner one of said tubes being stationary and the outer one of said tubes being movable to permit of access to the wick, a wick stop finger mounted within the inner combustion tube, the latter having an opening therein through which said finger is adapted to protrude into the path of movement of said wick, and cam means for engaging said finger to move it. 85

In testimony whereof, I have hereunto set my hand.

RUDOLPH HOFFMAN.
